UNITED STATES PATENT OFFICE.

GODFREY MORGAN, OF BUFFALO, NEW YORK.

PIPE CLEANER.

Application filed October 17, 1927. Serial No. 226,540.

This invention relates to a pipe cleaning outfit which is more particularly designed to permit of carrying this device in the pocket similar to the manner in which a fountain pen is now carried so that the same is always conveniently available for cleaning out the smoke conduit or channel of a pipe in case the same becomes more or less obstructed by particles of tobacco, dust or a moist nicotine slug. It is the object of this invention to provide an outfit of this character which is very simple and compact in construction and which is readily available for removing both hard and soft substances from the conduit of a pipe and which when assembled forms a practically air tight casing for the several cleaning members which have been used for removing the obstruction in the pipe and thereby avoids any unpleasant odors while carrying this device in the pocket.

In the accompanying drawings:—

Figure 1 is a side elevation of the preferred form of this pipe cleaning outfit which embodies my invention.

Figure 2 is a longitudinal section of the same showing the several parts assembled when not in use.

Figure 3 is a fragmentary longitudinal section of the lower part of the cleaning device in its assembled position on an enlarged scale.

Figure 4 is a cross section taken on the correspondingly numbered line in Fig. 3.

Similar characters of reference indicate like parts in the several figures of the drawings:—

The enclosing casing of this pipe cleaner, which is adapted to receive the cleaning elements coming directly in contact with the material which is removed from the pipe, consists preferably of a body and a cover, each of which is preferably made of one sheet of metal by suitable means, although these casing members may be constructed of any other suitable material.

As shown in the drawings, the body of the casing has a tubular wall 10 which is opened at its upper end so as to form an inlet therefor, while its lower end is practically closed by means of a lower head or bottom 11 which is provided with a central opening 12. The cover of the casing is constructed in the form of a cap having a tubular wall 13 which is open at its lower end and slips over the upper end of the body 10, while the upper end of the cap is closed by a head 14. The joint 15

between the cover and body of the casing is preferably made of conical form so that when these parts are pushed together, a telescopic joint is formed between the same which operates to frictionally connect them and hold them reliably in an assembled position without requiring any additional devices for this purpose.

For convenience in carrying this casing in the pocket the upper cap or cover may be provided with a clip or hook 16, as shown in Figs. 1 and 2, whereby this casing may be held against accidental displacement in the pocket, by engagement of this clip with the upper edge of the pocket in the same manner in which this is now commonly done with reference to fountain pens.

To the lower end of the casing is applied a lower cap which is preferably constructed of sheet metal, although other material may be used, so as to form a tubular side wall 17 adapted to engage the lower part of the periphery of the tubular body 10, and a lower head 18 which closes the lower end of this lower cap, and is adapted to engage with the head 11 at the lower end of the casing body, as shown in Figs. 2 and 3.

Arranged lengthwise within the casing and preferably axially therein when the parts are assembled, is a reaming rod or probe 19, the lower end of which passes through the central opening 12 in the bottom of the casing and is secured to the head of the lower cap while the upper end 20 of this reaming rod is preferably constructed in the form of a blunt drill so as to operate with a moderate cutting or clearing effect.

The lower end of this reaming rod is preferably so mounted on the head of the lower cap that the same is held both against lengthwise as well as turning movement thereon. This is preferably accomplished by providing the head 18 of the lower cap with an upwardly turned ferrule 21, the bore 22 of which is constructed square in cross section, as shown in Fig. 4, or of flat-sided form, and the lower part of the reaming rod is reduced to form a neck 23 which is also made square in cross section so as to fit the bore 22 of the ferrule, as shown in Fig. 4, or is of other suitable form in cross section for the purpose of preventing turning of the reaming rod in this lower cap. Lengthwise movement of the reaming rod in the ferrule is prevented by a downwardly facing shoulder 24 formed on the rod at the upper end of the re-

duced neck 23, and an upset flange 25 arranged at the lower end of the neck 23 and bearing against the underside of the head of the lower cap, as shown in Figs. 2 and 3.

5 When the device is not in use the lower cap 17 is applied to the lower end of the body with the reaming rod 19 projecting upwardly through the opening in the center of the bottom thereof and into the space within the 10 casing. When it is desired to use this reaming rod the lower cap is pulled off from the lower end of the tubular body and the reaming rod is withdrawn from the casing, after 15 which the free upper end of the reaming rod 15 can be pushed into the conduit of the mouth-piece or stem of a pipe for the purpose of removing any substantially hard obstructions which may be lodged therein. After 20 the hard material has been thus removed from the conduit of the pipe stem, any fine particles lodged therein may be further removed by pushing into this conduit a swab 26 of a kind now in common use and consisting of tufts of cotton which are secured between 25 twisted wires, so as to practically form a long rod-like brush. When the reaming or clearing rod 19 has been restored to the casing, a plurality of such swabs 26 may be stored within the space of the casing around 30 the clearing rod 19, as shown in Figs. 2 and 3, so that all the elements necessary for cleaning a pipe are all conveniently assembled in one case where they are available whenever required, and this casing also forms an 35 enclosure for the cleaning elements which prevents any odors from escaping and objectionably affecting the clothing.

In order to produce a tight friction fit between the lower cap and the lower end of the 40 body of the casing, the joint 27 between the opposing surfaces of these members is preferably made conical, as shown in Figs. 2 and 3 so that they are reliably held in a coupled position and will not become accidentally 45 separated while being carried in the pocket.

As a whole this pipe cleaner consists of comparatively few parts all of which are of simple construction and capable of being produced at low cost, and the same is also 50 very compact and thereby permitting of carrying the same in a coat or vest pocket and therefore ready for use at all times.

For the purpose of facilitation the turning 55 of the lower cap in order to tighten the same on the body of the casing or removing the

same therefrom, the lower part of the periphery of this cap is provided with a knurled or roughened surface 28, as shown in Fig. 1, in order to enable the fingers to obtain a firm hold thereon.

60

I claim as my invention:—

1. A device of the class described comprising a tubular body which is open at its upper end and provided at its lower end with a fixed head having an opening therein, and a 65 reamer adapted in the assembled position of the parts to project upwardly through the opening in said head and into the space within the body.

2. A device of the class described comprising 70 a tubular body having an open upper end through which cleaning swabs are inserted into the body and provided at its lower end with a fixed head having an opening, a cap having a tubular wall adapted to fit the exterior of the lower end of said body and a head on said cap arranged below the head of the body, and a reaming rod secured at its lower end to the head of said cap and adapted to project upwardly therefrom through the 75 opening in said head of the body and into the space within the latter.

3. A device of the class described comprising 80 a tubular body which is open at its upper end to receive cleaning swabs and provided at its lower end with a fixed head having an opening in the central part thereof, a cap having a tubular wall adapted to fit the exterior of the lower end of said body and a head on said cap arranged below the fixed 85 head of the body, a reaming rod secured at its lower end to the central part of the head of said cap and projecting upwardly therefrom through the opening in said head of the 90 body and into the space within the latter, and a cover secured to the upper end of said body.

4. A device of the class described comprising 95 a tubular body which is open at its upper end and provided at its lower end with a fixed head having an opening therein, a cap detachably engaging with the lower end of said body and having a head provided with an upturned ferrule adapted to project upwardly through said opening and a reaming rod secured at its lower end in said ferrule 100 and projecting upwardly through said opening and into the space within the body.

In testimony whereof I, hereby affix my signature.

GODFREY MORGAN.
